KNITTING MACHINE

Jacques Hennique, White Plains, N. Y.

Application August 19, 1952, Serial No. 305,145

Claims priority, application France October 24, 1951

10 Claims. (Cl. 66—4)

The present invention has for its object a knitting machine adapted to produce a stitched fabric and that is intended more particularly for domestic or handicraft use. It relates to the well known type of machine including two cooperating sets of members of a different nature, the members of one set being constituted by metal rods, pegs, pins, nails or the like parts which will be called hereinafter teeth and being interconnected to form a removable rectilinear comb, while the other set is constituted by hooks located in register with the free spaces provided between the successive teeth of the rectilinear comb and adapted to slide under the action of a driving member or carriage, housed inside the machine. The carriage that is started moving through the agency of a head controlled from the outside, has for its object to produce the forward and rearward movement of the sliding hooks that are constrained to reciprocate with reference to the rectilinear comb, with a view to positioning the thread in zig-zag formation between the teeth of the comb and the sliding hooks and thereby to initiating the successive rows of stitches after the formation of the first row.

It is a known fact that stitches are formed on machines of this type by passing the thread through the channel formed by the space provided between the hooks and the teeth of the rectilinear comb, when last mentioned hooks have progressed beyond the comb, after which the latter are caused to recede, so that the thread may assume its zig-zag shape, the thread drawn back by the hooks during their receding movement being thus locked at the upper ends of the comb teeth and the finishing of the row of stitches being performed through the knocking over of the preceding row of stitches over the upper ends of the teeth of the rectilinear comb. In order to prepare the following row of stitches, the comb has to be released with reference to its carrier and turned round longitudinally end for end or else it is left in or returned into its original position according to the kind of knitting that it is desired to obtain.

The present invention has for its object to bring various improvements to the machines of the above type, chiefly for making its structure simpler, its operation more reliable and more accurate, its handling and transportation easier, these different improvements having for their result an increased production.

These improvements that are applicable separately or in any desired combination are as follows:

According to a first object of the invention, the carriers on which the ends of the removable rectilinear comb rest are rigid each with an arm that is adapted to pivot round an axis perpendicular to the plane in which the hooks are shifted and that is at a comparatively large distance from the corresponding carrier, which allows adjusting the position of the teeth of the comb with reference to the sliding hooks and consequently provides for an adjustment of the stitch-size.

According to a further object of the invention, the above mentioned comb carriers are provided with a

2

pointer cooperating with a scale carried by the frame or casing of the machine, whereby it is possible to obtain an accurate adjustment and a marking of the position assumed by the rectilinear comb.

5 According to a still further object of the invention, each of the carriers of the movable rectilinear comb is provided on its inner surface with a recess adapted to cooperate with a stud carried by the corresponding end of the comb, said recess having two slopes one of which allows producing accurately a smooth rising movement of the rectilinear comb with a view to releasing the thread from the hooks while the other slope forms with the former slope a sort of funnel which allows readily positioning the comb and releasing it when it is to be turned round longitudinally end for end; at the same time each comb carrier is designed in a manner such that the comb may be readily turned upside down, i. e. the comb body carrying the teeth may be positioned higher than the teeth that are directed downwardly with a view to allowing examination of the knitted material, in which case the studs on the comb engage further recesses in the carriers that serve as abutments engaging the comb with a view to preventing the latter from dropping out too easily.

25 According to a further feature of the invention, the thread-carrier, associated with the carriage, for laying the thread in the sliding hooks at the moment of their forward movement while said carriage is being shifted, is provided with a rectangular head through which it may be taken hold of easily in order to impart to the carriage a translational movement.

According to a still further feature of the invention, the rectilinear comb includes a wooden core which allows an easy mounting and discarding of the teeth.

30 The machine may also include a parallelepipedic frame or casing housing a metal plate matching the inner shape of the frame and carrying the different members contained therein, while vertical slots serving as guide-ways for the sliding hooks are provided in the plate in register with further slots provided in the front wall of the frame and the rear raised ends of said hooks are guided during their sliding movement inside a transversely grooved metal sheet and their lower medial portions are guided inside another transversely grooved metal sheet; said two grooved metal sheets are secured to the first mentioned carrier plate and are rigid furthermore with a rail guiding the carriage producing the forward and rearward movement of the sliding hooks, which latter rest on a U-shaped metal sheet carried by springs bearing on stays connecting the two vertical flanges of the metal carrier plate.

55 Lastly, the machine may be laid on feet that are preferably removable and that include bearing surfaces in spaced formation, that allow giving the front surface of the frame a slope that furthers the execution of the work.

Further features and advantages of the invention will appear furthermore from the reading of the following description and inspection of accompanying drawings, said description and drawings referring to a preferred embodiment of the invention disclosed by way of example and by no means in a limiting sense. In said drawings:

60 Fig. 1 is a general perspective view of the machine;
Fig. 2 is a cross sectional view thereof;

Fig. 3 is a detail elevational view of one end of the machine;

65 Fig. 4 is a corresponding plan view.

The machine is constituted by a parallelepipedic elongated frame or casing 1 including a front wall 1a, a rear wall 1b, a bottom 1c, a cover 1d, said frame or casing being provided at either end with a removable cover 2.

70 Inside the casing 1 is housed a carrier 3 constituted by a metal plate forming in its upper part a longitudinal slot or groove 4 between the folded edges 3a and 3b of the

metal plate 3, said edges being fitted between the edges of a medial opening of the cover 1b that are folded at right angles; along said slot 4 the carriage or the like driving member described hereinafter is adapted to move. The front wall 1a of the casing is provided with vertical slots 5 through which project the sliding hooks 6, which latter rest on a longitudinal flange 7 formed on the wall 1a of the casing. The metal carrier plate 3 is also provided with vertical slots 8 registering with the slots 5.

Each of the sliding hooks 6 is constituted by a suitably bent metal rod and is guided at its front end inside the slots 5 and 8, by its rear end 6a guided inside the grooved metal sheet 9 and by its lower medial section 6b guided inside a grooved U-shaped sheet metal 10, the two sheets 9 and 10 being both carried by the carrier plate 3. The hooks 6 rest furthermore through their lower medial sections 6b on a metal sheet 11 assuming the shape of an inverted U and supported by springs 12 bearing on stays 13 connecting the two flanges of the carrier plate 3 together (Fig. 2).

The members with which the sliding hooks 6 cooperate for the formation of stitches may be constituted for instance by a series of metal rods assuming the shape of nails or teeth 14. The latter are connected so as to form a rectilinear removable comb 15 that may be constituted by a tubular body inside which is housed a wooden core 16 that allows the ready mounting and dismantling of the nails or teeth 14 without it being necessary to resort to any special device for these operations. The removable rectilinear comb 15 carries at each end a plate 17 secured to the wooden core 16 through the agency of a screw 18 (Fig. 3), said plate being provided with a stud 19 bearing against the bottom of a V-shaped recess 20 formed in the inner surface of the corresponding support 21 (Fig. 4). Each support 21 is rigid with an arm 22 that may be shifted angularly with reference to a stationary spindle 23 perpendicular to the upper wall of the frame casing and consequently to the plane in which the hooks slide. Said spindle 23 is carried by a plate 24 rigid with the casing 1. The shifting of the supports 21 is guided and limited by a slot 25 provided in the arm 22 and cooperating with a threaded pin 26 screwed into the plate 24; the large radius of curvature assumed by the slot 25 as allowed by the location of the spindle 23 ensures substantial linearity of the movement of the carrier 21 in a horizontal plane. The threaded pin 26 includes a head 27 provided with a polygonal recess 28 adapted to receive a wrench providing for the clamping or releasing of the pin 28, whereby it is possible to adjust the location of the carrier 21 and to hold same fast in said adjusted position through engagement of the head 27 with the edges of the slot 25.

Each of the supports 21 is rigid with a pointer 29 moving over a scale 30 carried by the casing and that allows thus an accurate adjustment and marking of the location of the rectilinear comb. It is possible by adjusting the position of the comb with reference to the sliding hooks to adjust the size of the stitch and consequently to obtain as desired looser or closer knitted fabrics.

The V-shaped recess 20 provided on the inner surface of each support 21 has two slopes of which one, 20a (Fig. 2) is adapted to provide accurately a smooth rising movement of the rectilinear comb 15 when it is desired to release the thread from the hooks. The other slope 20b forms with the slope 20a a sort of funnel or guideway that allows easily positioning the comb and releasing it when it has to be turned longitudinally end for end.

Lastly, the support 21 is designed in a manner such that the comb may be easily turned upside down, the tubular body lying uppermost and the teeth being directed downwardly to allow examination of the knitted fabric when this is necessary. When the comb is thus turned upside down, the stud 31 carried by the end plate 75

17 (Fig. 3) engages a corresponding recess 20c that serves as an abutment and as hooking means with a view to preventing the comb from dropping back too easily.

In the position of the comb illustrated in the drawings, 5 each stud 31 bears against the adjacent carrier 21 so as to hold the rectilinear comb 15 at a certain distance from the front wall 1a of the casing 1 (Fig. 3).

The teeth 14 are located, when the comb 15 is in its 10 normal position, in a manner such that the hooks 6 may lie in register with the intervals between said teeth. The hooks 6 are actuated in a manner such as to execute 15 in alternation a forward and a rearward movement with reference to the comb 15, this reciprocating movement being produced by a driving sliding member such as the carriage shown at 32 (Fig. 2) which is adapted to assume a reciprocating movement throughout the length of the machine. This movement is produced through hand-actuation of the head or knob 33, assuming the shape of a parallelepiped and forming a handle for the carriage. 20 The said carriage 32 slides when thus controlled over a longitudinal rail 34 carried by the grooved metal sheet 10. To this carriage 32 are secured at 35 and 36 the ends of 25 an endless metal strip or ribbon 37 that serves for holding the sliding hooks 6 in their rear position and that is guided in a longitudinal groove 38 provided in the rail 34; said metal ribbon is drawn on one side and pushed on the other during the movement of the carriage 32, the two movements of the ribbon equilibrating each other without any difficulty, whereby the operation of the machine is extremely smooth. The head 33 of the carriage 30 32 carries the usual thread carrier 39 that provides for the laying of the thread in the usual manner.

In order to make the counting of the stitches easier, one 35 tooth out of five, for instance, in the series of teeth 14 carried by the rectilinear comb 15, may be colored differently from the others whereby it may be easily distinguished; this is shown at 14a in Fig. 4.

On the other hand, it is possible to make the stitches 40 pass over the heads of the teeth when the knitting is that of jersey stitches, and to this end combs are used that include teeth in register only with a number of the intervals between adjacent sliding hooks.

The machine is carried by two removable feet constituted each by a flat iron member 40 provided with two 45 upwardly bent flanges 41 and 42 engaging the bottom of the casing 1, one of the flanges 41 bearing against a plate 43 rigid with the casing. Each of the flat iron members 40 is rigid with an iron fitting 44 provided with a reinforcing rib 45 and that is suitably bent so as to form 50 widely spaced bearing surfaces carrying the iron member 40; said bearing surfaces carry blocks 46 of elastic material such as rubber for instance. This arrangement allows giving the front of the machine a slope furthering the work as readily apparent in Fig. 2, while the mounting and dismantling of the machine may be performed 55 speedily.

Obviously the invention is by no means limited to the 60 particular embodiment disclosed by way of example, as many modifications and the substitution of equivalent means for the different parts thereof may be contemplated, without unduly widening thereby the scope of the invention as defined in the accompanying claims.

What I claim is:

1. A knitting machine comprising a frame, a series of 65 aligned thread-engaging hooks, controlling means for urging said hooks in succession into a transverse reciprocatory movement, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolubly secured to allow a substantially rectilinear transverse shifting of the comb carriers with reference to the series of hooks and

means adapted to lay a thread between the shifted hooks and the teeth of the comb.

2. A knitting machine comprising a frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolvably secured to allow a substantially rectilinear transverse shifting of the comb carriers with reference to the series of hooks and means adapted to lay a thread between the shifted hooks and the teeth of the comb.

3. A knitting machine comprising a frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, an inwardly recessed carrier at each end of the comb, a stud rigid with each end of the rectilinear comb and removably carried in the recess of the corresponding carrier, a pivoting arm of substantial length rigid with each carrier, pivots rigid with the frame on the outside of the comb and to which said arms are revolvably secured to allow a substantially rectilinear transverse shifting of the comb carriers with reference to the series of hooks and means adapted to lay a thread between the shifted hooks and the teeth of the comb.

4. A knitting machine comprising a frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, an inwardly recessed carrier at each end of the comb, the recess in each carrier being defined by two slopes, the cross-section of which by a plane perpendicular to the line of hooks assumes the shape of a V over one side of which the comb is adapted to be raised to an adjustable extent for releasing a thread from the hooks, said V-shaped recess guiding the engagement and disengagement of the comb and allowing a longitudinal turning round of the comb end for end, a stud rigid with each end of the rectilinear comb and removably carried in the recess of the corresponding carrier, a pivoting arm of substantial length rigid with each carrier, pivots rigid with the frame on the outside of the comb and to which said arms are revolvably secured to allow a substantially rectilinear transverse shifting of the comb carriers with reference to the series of hooks and means adapted to lay a thread between the shifted hooks and the teeth of the comb.

5. A knitting machine comprising a frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, an inwardly recessed carrier at each end of the comb, the recess in each carrier being defined by two slopes, the cross-section of which by a plane perpendicular to the line of hooks assumes the shape of a V over one side of which the comb is adapted to be raised to an adjustable extent for releasing the thread from the hooks, said V-shaped recess guiding the engagement and disengagement of the comb and allowing a longitudinal turning round of the comb end for end, a stud rigid with each end of the rectilinear comb and removably carried in the recess of the corresponding carrier, a further recess being provided in each carrier to form a stop for the comb when its studs are inserted upside down in the carrier recesses and its teeth are directed downward-

ly, a pivoting arm of substantial length rigid with each carrier, pivots rigid with the frame on the outside of the comb and to which said arms are revolvably secured to allow a substantially rectilinear transverse shifting of the comb carriers with reference to the series of hooks and means adapted to lay a thread between the shifted hooks and the teeth of the comb.

6. A knitting machine comprising a frame, a series of aligned thread-engaging hooks, a carriage moving longitudinally of the machine for controlling the transverse reciprocation of the hooks, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolvably secured to allow a substantially rectilinear transverse shifting of the comb carriers with reference to the series of hooks, a thread carrier rigid with the movable carriage and adapted to lay a thread inside the sliding hooks as they reciprocate transversely under the action of the shifting of the carriage and a hand operable projection rigid with said thread carrier through which said thread carrier and carriage may be shifted in unison.

7. A knitting machine comprising a frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, said comb including a longitudinal wooden core, a cover portion fitted over said core and teeth secured to the wooden core and projecting upwardly with reference thereto, a carrier for each end of the comb, a pivoting arm of substantial length rigid with each carrier, pivots rigid with the frame on the outside of the comb and to which said arms are revolvably secured to allow a substantially rectilinear transverse shifting of the comb carriers with reference to the series of hooks and means adapted to lay a thread between the shifted hooks and the teeth of the comb.

8. A knitting machine comprising a parallelepipedic frame, a series of aligned thread-engaging hooks, controlling means for urging said hooks in succession into a transverse reciprocatory movement, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolvably secured to allow a substantially rectilinear transverse shifting of the comb carriers with reference to the series of hooks, means adapted to lay the thread between the shifted hooks and the teeth of the comb, a bent metal plate fitted between the longitudinal walls of the frame extending throughout the latter and provided with apertures to allow the hooks to be shifted transversely through said apertures, a slideway for the means controlling the reciprocation of the hooks extending longitudinally inside said metal plate, perforations being provided in the front wall of the frame in register with the apparatus in the plate for the passage of the sliding hooks and two transversely grooved metal sheets carried inside the metal plate and provided with transverse grooves for the guiding of the inner ends and the medial portions respectively of the different hooks.

9. A knitting machine comprising a parallelepipedic frame, a series of aligned thread-engaging hooks, a carriage moving longitudinally of the machine for controlling the transverse reciprocation of the hooks, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolvably secured to allow

a substantially rectilinear transverse shifting of the comb carriers with reference to the series of hooks, a thread carrier rigid with the movable carriage and adapted to lay the thread on the sliding hooks as they reciprocate transversely under the action of the shifting of the carriage, a hand operable projection rigid with said thread carrier through which said thread carrier and carriage may be shifted in unison, a bent metal plate fitted between the longitudinal walls of the frame and extending throughout the latter and provided with apertures to allow the hooks to be shifted transversely through said apertures, a slideway for the carriage controlling the reciprocation of the hooks, extending longitudinally inside said metal plate, perforations being provided in the front wall of the frame in register with the apertures in the plate for the passage of the sliding hooks and two transversely grooved metal sheets carried inside the metal plate and provided with transverse grooves for the guiding of the inner ends and the medial sections respectively of the different hooks.

10. A knitting machine comprising a parallelepipedic frame, a series of aligned thread-engaging hooks, a carriage moving longitudinally of the machine for controlling the transverse reciprocation of the hooks, a rectilinear comb located in front of the aligned hooks and adapted to cooperate therewith for the formation of the knitted fabric, a carrier for each end of the comb, a pivoting arm of substantial length rigid with each carrier, pivots rigid with the frame on the outside of the comb and to which said arms are revolvably secured to

allow a substantially rectilinear transverse shifting of the comb carriers with reference to the series of hooks, a thread carrier rigid with the movable carriage and adapted to lay a thread on the sliding hooks as they reciprocate transversely under the action of the shifting of the carriage, a hand operable projection rigid with said thread carrier through which said thread carrier and carriage may be shifted in unison, a bent metal plate fitted between the longitudinal walls of the frame, extending throughout the latter and provided with apertures to allow the hooks to be shifted transversely through said apertures, a slideway for the carriage controlling the reciprocation of the hooks, extending longitudinally inside said metal plate, perforations being provided in the front wall of the frame in register with the apertures in the plate for the passage of the sliding hooks and two transversely grooved metal sheets carried inside the metal plate and provided with transverse grooves for the guiding of the inner ends and the medial portions respectively of the different hooks, a further metal sheet assuming the shape of an inverted U on which the medial portions of the hooks are adapted to slide, a spring carrying the inverted U-shaped sheet and stays connecting the outer edges of the metal plate at the lower end thereof and carrying said spring.
